United States Patent Office

Des. 186,701
Patented Nov. 17, 1959

186,701

DESK BASE FOR WRITING INSTRUMENTS

William E. L. Bunn, Fort Madison, Iowa, assignor to W. A. Sheaffer Pen Company, Fort Madison, Iowa, a corporation of Delaware

Application August 6, 1958, Serial No. 52,072

Term of patent 14 years

(Cl. D74—1)

FIG. 1

FIG. 2

Fig. 1 is a top plan view of a desk base for writing instruments showing my new design;

Fig. 2 is a side elevational view; and

Fig. 3 is a side perspective view thereof. The dotted line showing of a pen in Fig. 3 is for illustrative purposes only.

I claim:

The ornamental design for a desk base for writing instruments, substantially as shown and described.
